UNITED STATES PATENT OFFICE.

PETER ERICKSON, OF CHICAGO, ILLINOIS.

CUTTER-GUARD.

1,240,430.

Specification of Letters Patent. Patented Sept. 18, 1917.

Application filed July 22, 1916. Serial No. 110,678.

To all whom it may concern:

Be it known that I, PETER ERICKSON, a citizen of the United States, residing at Chicago, in the county of Cook and State of Illinois, have invented new and useful Improvements in Cutter-Guards, of which the following is a specification.

This invention relates to guards for saws and other wood-working machines to prevent injury to the operator from contact with the saw or other cutting tool.

The invention has for its object to provide a simple and efficient guard device having a wide range of adjustment, and which can be easily swung into and out of operative position.

With the object stated in view, the invention consists in a novel combination and arrangement of parts to be hereinafter described and claimed, and in order that the same may be better understood, reference is had to the accompanying drawings forming a part of this specification.

In the drawings,

25 Figure 1 is an elevation of the device showing its application, and

Fig. 2 is a plan view thereof;

Fig. 3 is an enlarged side elevation of a portion of the device, partly in section, and

30 Fig. 4 is a front elevation thereof;

Fig. 5 is a side elevation of the guard;

Fig. 6 is an enlarged cross section on the line 6—6 of Fig. 5;

Fig. 7 is an enlarged cross section on the line 7—7 of Fig. 1;

Fig. 8 is a perspective view showing a modified form of guard, and

Fig. 9 is a cross section on the line 9—9 of Fig. 8.

40 Referring specifically to the drawings, 10 denotes the top of the table of a wood-working machine, such as a sawing machine, shaper, or the like. The tool in the present instance is a saw 60. The table has a depending apron 11 on which the device which is the subject matter of the present application for patent is mounted.

On the apron 11 is mounted a wide bracket having a base plate 13 which is secured to the apron by bolts 14 or other suitable means. The bracket also has a medial web 12, a vertical plate 15 parallel to and spaced from the base plate 13, a horizontal top plate 16 and a similar but larger bottom plate 17, said top and bottom plates being

spaced and formed with vertical bearings 19 and 20, respectively, in which is mounted an upright shaft 18.

On the shaft 18, between the upper bearing 19 and the plate 17, is fitted a sleeve 21 60 reinforced by a top rib 22, said sleeve being split lengthwise and extended to form two outstanding vertical plates or flanges 23 and 24 arranged side by side in laterally spaced relation. Between these two plates is slidably mounted a plate 25, which latter, at the end of its inward stroke, is adapted to seat, similar to a key, in a longitudinal groove 26 in the shaft 18, the movement of the plate being lateral, or toward and from 70 the shaft. When the key-plate 25 is thus advanced, the sleeve 21 and its plates 23 and 24 are locked to the shaft 18, and when the key-plate is backed out of the shaft groove, the shaft and the sleeve are uncoupled and 75 the shaft is free to turn in the sleeve. Vertical sliding movement of the sleeve on the shaft is prevented by the bearing 19 and the plate 17 between which the sleeve is positioned. The plates 23, 24 and 25 have aligned 80 apertures to take a transverse bolt 27, the plates 23 and 24 having outward reinforcements 28 and 29 to provide a bearing for the bolt, and the reinforcement 28 is tapped to take the threaded end of the bolt shank. 85 The bolt head has an actuating lever 30 for turning the same to draw the plates together. The plate 25 also has a horizontal slot 31 through which passes a short pin 32 the ends of which are fixed in the plates 23 and 24. 90 This slot and pin limit the sliding movement of the plate 25 hereinbefore described. The aperture in the plate 25 for the bolt 27 is elongated sufficiently to allow the plate to be slid as described. 95

To operate the key plate 25, a lever 33 is provided, the upper end of which serves as a handle, and the lower end as a fulcrum, the same seating in a notch 36 made in the plate 24. The plate 24 is cut away obliquely, as shown at 34, to accommodate the lever in a position alongside the plate 25. Intermediate its ends, the lever is loosely riveted to the plate 25, as shown at 35. In Fig. 3 the plate 25 is shown in advanced position to 100 couple the sleeve 21 to the shaft 18 by its insertion into the groove 26, and if the lever 33 is swung to the dotted position, the plate will be retracted to uncouple the sleeve and the shaft. 105 110

The plate 23 has a webbed enlargement 37 integral with the part 28 and provided with two lateral extensions 38 which are slotted as shown at 39 and straddle the plate 17, 5 the latter having a curved edge. Set screws 40 are threaded through the parts 38, from the bottom thereof, and engage the plate 17 to lock the sleeve 21 and the parts carried thereby to any position they may be swung 10 after having been locked to the shaft 18.

The shaft 18 is held up or balanced by a counterweight 41 carried by a cable 41^a passing over a grooved pulley 41^b mounted on a bottom extension of the bracket web 12, the 15 cable being suitably connected to the lower end of the shaft. A collar 42 is adjustably fixed to the shaft above the bearing to limit its downward movement. The collar has a key 43 seating in the shaft groove 26.

20 The shaft 18 rises from the bracket 12 a suitable distance, and its upper end supports a horizontal plate 44, the latter having a bearing 45 through which the shaft passes. A key 46 seating in the shaft groove 26 and 25 in a registering groove in the bearing, locks the plate 44 against turning on the shaft. A screw 47 threaded sidewise through the bearing and acting on the key 46, locks the same to hold the plate 44 fixed on the shaft.

30 The plate 44 has two upstanding end flanges 48 provided with laterally spaced apertures in which slidably seat horizontal rods 49. These rods are adjustable lengthwise, and they are held in adjusted position 35 by a transverse double-jawed clamping member 50 operated by a screw 51 threaded into an enlargement 52 on the top of the plate 44.

The rods 49 extend across the table 10 and terminate above the saw or other tool 60, 40 where they carry a combined clamp and spacer block 53 having a bottom enlargement in the form of a circular plate 54. On the under side of the plate 54 is mounted a block 55 of circular contour and having an 45 outstanding marginal flange 56 at the top, said flange being in contact with the plate 54, and so held by a clamp 56^a.

The block 55 has two depending, transverse and laterally spaced, bottom projections 57, the inner faces of which are grooved to form a slideway for a plate 58, which 50 may be secured in fixed position by a screw 59 threaded into the bottom of the part 54 and passing through a slot in the plate 58 55 and the part 55 as shown in Fig. 6.

The parts thus far described form an adjustable support for the guard associated with the tool 60. This guard has the shape of a hood made up of two laterally spaced 60 open-work side members 61 connected by a solid top portion 62. The guard straddles the saw 60 and it is segmental. Each side member is fitted with a glass pane 63 to render the saw visible. The guard has two 65 transversely apertured ears 64 at the top,

and two similar ears 65 are on the bottom of the plate 58. The ears 64 and 65 are connected by parallel links 66, whereby the guard is pivotally supported from the plate 58. This suspension permits the guard to 70 be swung back as shown dotted in Fig. 5 in the direction of its length, whereupon it also rises to a sufficient height to allow the work to be pushed under the guard past the saw. When the work has passed the saw, the 75 guard drops back and again completely encloses that portion of the saw which projects above the table 10.

To facilitate the easy engagement of the work with the guard 61, the receiving end 80 of the latter is provided with two scroll springs 67.

A modified guard is shown in Figs. 8 and 9. This device is also attached to the plate 58 and comprises a spring nose guard 68 at 85 the receiving end for holding down the advancing work, and a pivoted rear end guard 69 to prevent the work from accidentally flying over and forward with the saw and striking the operator. The parts 68 and 69 90 are attached to the plate 58. The part 68 is slotted, as shown at 70, to permit the saw teeth to pass freely, the sides of the slot closing in on the saw blade back of the teeth to keep the guard centered. The opposite end 95 of the plate 58 has apertured ears 71, one pair to hold a U-shaped rod 71^a which pivotally supports the guard member 69, and the other pair to hold a spring rod 72 carrying a marginal guard 73 along which the work 100 slides on the table 10. The rods 71 and 72 are secured to the plate 58 by bolts 74 through the heads of which they pass, as shown in Fig. 9, said bolts being provided with nuts 75 on the top of the plate. A nut 76 prevents the guard 69 from sliding off the rod 71^a.

Although the device shown in Fig. 8 has been shown separate and may be so used, it may also be incorporated with the guard 110 shown in Fig. 5.

In use, the device is substantially in the position shown in Figs. 1 and 2, the screws 40 having been tightened and the lever 33 advanced if the usual position of the rods 49 115 is at right angles to the table edge, as shown in full lines in Fig. 2. If, occasionally, the guard is to be used on a tool located at another portion of the table 10, the lever 33 may be retracted to release the shaft 18 from the sleeve 21, and the screw 59 loosened, after which the support can be swung horizontally to assume the position shown dotted in Fig. 2, or any other desired position within the range of adjustment, the shaft now 120 turning in the sleeve. By loosening the screw 59 the plate 58 carrying the guard may be kept parallel to the table edge. The screws 40 need not be loosened, as with the last-described adjustment the groove 26 in 130

the shaft 18 will have swung away from the key plate 25, and the plates 23, 24 and 25 may be made tight by the bolt 27, with the lever 33 retracted, there being sufficient clearance between these plates to cause the sleeve 21 to firmly bind the shaft 18 in the newly adjusted position when the bolt 27 is operated. The screws 40 are only loosened when permanent work is to be done with the rods 49 at a new angle. Ordinarily when the guard is to be lifted off at the close of the day for cleaning the saw or other tool, the bolt 27 is loosened and the lever 33 is retracted, this loosening the shaft 18 so that it may be rotated to swing the guard away from the saw, the shaft being first raised until the guard clears the saw.

Various other types of guards besides the ones described hereinbefore may be attached to the plate 58.

I claim:—

1. The combination of a support, a shaft carrying the support and having a longitudinal groove, a bearing bracket rotatably supporting the shaft, a sleeve mounted on the shaft, a key carried by the sleeve and adjustable to seat in the shaft groove, and

means for locking the sleeve to the bearing bracket.

2. The combination of a support, a shaft carrying the support and having a longitudinal groove, a bearing bracket rotatably supporting the shaft, a split sleeve encircling the shaft and having outstanding flanges at its ends, a key slidably mounted between said flanges and adapted to enter the shaft groove, a lever connected to the key for actuating the same and having its fulcrum on one of the flanges, and means for locking the sleeve to the bearing bracket.

3. The combination of a support, a shaft carrying the support and having a longitudinal groove, a bearing bracket rotatably supporting the shaft, a split sleeve encircling the shaft and having outstanding flanges at its ends, a key slidably mounted between said flanges and adapted to enter the shaft groove, a lever connected to the key for actuating the same and having its fulcrum on one of the flanges, means for locking the sleeve to the bearing bracket, and means for clamping the key between the flanges.

In testimony whereof I affix my signature.

PETER ERICKSON.
